[57] CLAIM

The ornamental design for a combined hand-held computer housing and cover, as shown and described.

DESCRIPTION

FIG. 1 is a bottom front and left side perspective view of a combined hand-held computer housing and cover showing my new design;

FIG. 2 is an enlarged front elevational view thereof;
FIGS. 3 and 5 are bottom and top plan views thereof,
respectively;

FIG. 4 is a left side elevational view thereof with the right side being a mirror-image; and,

FIG. 6 is a rear elevational view thereof.

*Fig. 1**Fig. 2**Fig. 3**Fig. 4**Fig. 5**Fig. 6*
